UNITED STATES PATENT OFFICE.

RUSSELL D. HOLABIRD, OF OAKLAND, CALIFORNIA.

DESIGN FOR A FRAME FOR ICE AND REFRIGERATING MACHINES.

SPECIFICATION forming part of Design No. 28,897, dated June 21, 1898.

Application filed May 25, 1897. Serial No. 638,175. Term of patent 7 years.

To all whom it may concern:

Be it known that I, RUSSELL D. HOLABIRD, a citizen of the United States, residing at Oakland, in the county of Alameda and State of California, have invented and produced a new and original Design for Frames of Ice and Refrigerating Machines, of which the following is a specification, reference being had to the accompanying drawing, forming a part thereof.

The said drawing is a view in perspective of my said design.

The leading or material features of my said design, as shown in the drawing, consist of a rectangular box-base with perpendicular sides and ends and a flat top, in the center of which stands a rectangular casing or chest having straight parallel sides, parallel ends, and a flat top, the dimensions of said casing in height, breadth, and length being much less than the similar dimensions of the box-base. From the flat top of the casing, projecting upward, are two pump-cylinders smaller in diameter than the width of the top, and on the upper ends of each cylinder a flat top or head, from which springs a short cylindrical housing with a flat top or head.

The housing on the aforesaid cylinders are of equal height and diameter and are united by a horizontal cylindrical bridge extending longitudinally between the adjacent sides of the housings. In the center of the bridge are bosses or necks for coupling pipes. Situated on the same longitudinal center line are two upright trap-chambers, of cylindrical shape, with flat tops and contracted lower

portions that spring from the flat top of the box-base or main rectangular body of the frame alongside of the rectangular casing or chest and between the ends thereof and the ends of the said base. The last-named cylinders have contracted lower ends where they spring from the flat top and are of equal height and at equal distances apart with relation to the smaller cylinders upon the chest. The said trap-chambers have apertures in the top for connecting pipes or tubes thereto, and in the side of the chest are flanged apertures for pipe connections.

In the sides and ends of the box-base are openings of curved or oval outline.

In the drawing, A indicates the box-base or main body of the frame; B, the casing or chest on the top; C C, the pump-cylinders; D D, the valve-chests; E, the bridge between the two chests, and F F the cylindrical trap-chambers.

G G are the bosses on the bridge, and H H the apertures in the top of the trap.

Having thus fully described my invention, what I claim as new, and desire to secure by Letters Patent, is—

The design for a frame for an ice and refrigerating machine, substantially as herein shown and described.

In testimony that I claim the foregoing I have hereunto set my hand.

RUSSELL D. HOLABIRD.
